(57) **CLAIM**

The ornamental design for a camera for mobile phone, as shown and described.

DESCRIPTION

FIG. 1 is a perspective view of a camera for mobile phone showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof where the camera is recessed in a mobile phone;

FIG. 10 is a perspective view thereof where the camera is in a configuration of use.

FIG. 11 is an enlarged view of portion 11 shown in FIGS. 2; and,

FIG. 12 is an enlarged view of portion 12 shown in FIG. 9. The evenly dashed broken lines in the drawings depict portions of the camera for mobile phone that form no part of the claimed design. The dash-dot-dash broken lines in the drawings depict boundary lines around areas and form no part of the claimed design.

1 Claim, 12 Drawing Sheets
